APPARATUS FOR GALVANIZING

Raymond J. Wean, Hans E. Melin, and Elmore R. Berk, Warren, Ohio, assignors to The Wean Engineering Company, Inc., Warren, Ohio, a corporation of Ohio

Application December 30, 1939, Serial No. 311,810

11 Claims. (Cl. 91—12.5)

This invention relates generally to the application of a protective coating to sheet material and, specifically, to an apparatus for galvanizing ferrous sheets.

One of the methods which has been employed heretofore for the galvanizing of ferrous sheets is the so-called lead-zinc process. It is characterized, however, by certain serious objections. An improvement therein is disclosed and claimed in the copending application, Ser. No. 256,684, of Wean et al. The present invention provides an improved method and apparatus following the general principles of operation disclosed in said application.

The thickness of the zinc coating applied to ferrous sheets in the lead-zinc process varies with the depth of the bath of molten zinc through which the sheets are passed. The principal object of the present invention is to provide a method and means whereby the depth of the zinc bath may readily be altered as desired, without the necessity of changing the amount of lead in the molten bath thereof on which the zinc bath floats. In a preferred embodiment and practice of the invention, the zinc bath is contained in an inner pot having means for adjusting it vertically in the lead bath. Exit rolls are journaled in housings mounted in the zinc pot for adjustment vertically thereof, both the exit rolls and the zinc pot being adjustable independently of the remainder of the galvanizing rig which may be largely of conventional construction. Further advantages of the invention will become apparent during the course of the following detailed description which refers to the accompanying drawings illustrating a preferred embodiment and practice. In the drawings—

Fig. 1 is a partial plan view of a galvanizing apparatus embodying the invention;

Fig. 2 is a longitudinal sectional view taken along the plane of line II—II of Fig. 1;

Fig. 3 is a partial section to enlarged scale taken along the plane of line III—III of Fig. 1;

Fig. 4 is a partial plan view showing the drive for the exit rolls;

Fig. 5 is a sectional view taken along the plane of line V—V of Fig. 4;

Fig. 6 is a sectional view taken along the plane of line VI—VI of Fig. 4;

Fig. 7 is a plan view of the zinc pot;

Figs. 8 and 9 are sectional views taken along the planes of lines VIII—VIII and IX—IX, respectively, of Fig. 7;

Fig. 10 is a sectional view to enlarged scale 55

showing a portion of the apparatus illustrated in Fig. 2; and

Fig. 11 is a view similar to Fig. 6 showing the parts in alternative position.

Referring now in detail to the drawings, the apparatus of our invention comprises a lead pot 10 having a sheet-feeding and guiding rig 11 removably disposed therein. A zinc pot 12 is provided with a removable sheet-feeding rig 12a including exit rolls 13 and is disposed adjacent the discharge end of the pot 10.

The rig 11, for the most part, represents a slight modification of conventional construction and will, therefore, be described only generally.

15 It comprises a main frame including housings 14 connected by tie rods 15. Entering rolls 16 journaled in suitable bearings carried on the housings 14 receive sheets advancing between the guides 17 and direct them through a flux box 18 and thence between guides 19. Bottom feed rolls 20 are journaled in bearings adjustable in windows 21 formed in the housings 14 and deliver the sheets respectively to guides 22 and 23. The lower roll of each set of bottom rolls 20 is driven by 20 motors (not shown) mounted on a laterally adjustable base plate 28, through suitable reducing gears. The feed-in rolls 16 are driven through a chain and sprocket drive 29 by another motor and reducing gear operating a shaft 30.

25 The upper roll of each set of bottom rolls is 35 pressed downward by counter-weighted levers 31 pivoted at 32 to brackets 33 and 33a, acting through struts 34. Bearing brackets 35 are pivoted to the brackets 33 coaxially of the shafts 27 and are provided with bearings in which the upper ends of the shafts 25 are journaled. This 40 construction, as well as an alining pin 36 on the base plate 28 and a cooperating socket 37 on one of the brackets 33, is more fully described and claimed in a copending application, Ser. No. 308,798 of Holdgate et al.

45 The zinc pot 12 comprises a main reservoir 38 and an overhanging portion 40 having a bottom opening 41 between a reservoir wall 38a and a shelf 40a. Guides 42 extending into the opening 50 cooperate with the guides 23 to feed sheets between the exit rolls 13. Housing pockets 43 and 44 are formed adjacent the ends of the pot 12. A float chamber 45 communicates with the pocket 44. The pot 12 is preferably fabricated from suitable plate by welding.

The lead pot 10 has posts 46 welded to the upper edge thereof. The pot 12 has angles 47 extending around the rim thereof and welded thereto. The angles 47 have holes 48 therein which the posts 46 are adapted to enter when the pot 12 is lowered into the pot 10. The posts 46 have holes therethrough adapted to receive wedges 49 bearing on the angles 47. The tops of the holes in which the wedges are inserted are at slightly different levels so that when one wedge is tight, the other will be free for easy removal.

When the pot 10 is filled with molten lead to a suitable level such as that indicated by the dotted line 50 and the pot 12 is filled with zinc to the level indicated by the dotted line 51 through the axes of the exit rolls 13, the pot 12 will be buoyed up by a force equal to the difference between the densities of lead and steel multiplied by the volume of lead displaced by the side walls and bottom of pot 12 plus the force equal to the difference between the densities of lead and zinc multiplied by the volume of lead displaced by the reservoir portion 38 of the pot 12. The pot 12, therefore, tends to float and the posts 46 and wedges 49 serve to hold the pot in predetermined relation to the lead pot 10. If the wedges are backed out, the pot 12 is raised. Conversely, the pot 12 may be forced downward by driving the wedges in farther. The wedge holes are deep enough to permit the desired range of adjustment of the pot 12.

The rig 12a is adjustably mounted on guide pins 52 secured to the pot 12 and extending upwardly through the angles 47. It comprises an auxiliary frame including housings 53 with holes adjacent the ends thereof through which the pins 52 extend as the housings are disposed in the pot with their lower portions in the pockets 43 and 44. The housings are held in vertically adjusted position relative to the pot 12 by spacer blocks 54 and keys 55. The housings have notches 56 providing bearing surfaces for supporting the necks of the exit rolls 13. Keeper arms 57 pivoted at 58 to brackets secured to the housings, hold the rolls in position in the notches 56. The arms 52 are urged in the roll-securing direction by a spring-bolt assembly 59. The guides 42 are secured to the housings 53, and move with the rig 12a.

The exit rolls 13 have meshing gears 60 at one end thereof. A gear 61 at the other end of one of the rolls meshes with a driving gear 62. The gear 62 is driven by a motor 63 through a speed reducer 64. The motor and reducer are mounted on a base plate 65 which is slidable laterally on wedge blocks 66. The wedge blocks 66 are movable toward or from each other in a sub-base 67 to adjust the base 65 vertically. Screw shafts 68 having right and left-hand threads at opposite ends thereof, cooperate with nuts secured to the wedge blocks and are connected together by a chain and sprocket drive 69. Lateral adjustment of the base 65 on the wedge block 66 is effected by a screw 70. The screw 70 cooperates with a nut 71 positioned in a cored well 72 in the base 65. The base 65 may thus be adjusted vertically relative to the nut 71 and operation of the screw 70 causes lateral adjustment of the base 65. The screw shafts 68 and the screw 70 are journaled in combined thrust and radial bearings 73 mounted on the sub-base 67.

It will be apparent that by adjusting the base 65 upwardly, the driving gear 62 will clear the upper edge of the pot 12 and that lateral adjust-

ment of the base 65 away from the pot will clear the latter to permit it to be removed from the lead pot 10 when necessary.

A float 74 (see Figs. 1 and 3) is disposed in the float chamber 45 and has a stem 75 reciprocable through an eye 76 mounted on the adjacent side wall of the pot 12. The float 74 is so constructed that it will float on the lead bath but will sink in the zinc bath. Its function is to indicate the level of the lead-zinc interface, in a manner which will appear shortly.

Deflectors 77 and a "bull tail" 78 are mounted on the rim of the pot 12 for directing a sheet emerging from between the rolls 13 onto a conveyor.

Fig. 10 illustrates the positions of the pot 12 and exit rolls 13 for the minimum depth of zinc baths. The pot 12 is at its uppermost position relative to the pot 10 and the housings 53 in which the rolls 13 are journaled are at their lowermost position relative to the pot 12. The level of lead in the pot 10 is shown at 50 and the level of zinc in the pot 12 is shown at 51 as in Fig. 2. The level of the zinc coincides substantially with the axes of the rolls 13. The lead-zinc interface is indicated at 79 and is substantially at or slightly below the level of the shelf 40a. Because of the difference between the specific gravities of lead and zinc, the height of the zinc column above the interface 79 is slightly greater than the height of the lead bath thereabove.

With the adjustment of the parts illustrated in Fig. 10, sheets fed through the entering rolls 16 pass through the flux box 18 and thence through the lead bath, being guided therethrough by the guides 19, 22, 23 and advanced by the feed rolls 20. The sheets finally pass upwardly through the bottom opening 41 in the overhanging portion 40 of the pot 12 and between the exit rolls 13. The lead bath serves to preheat the sheets but does not coat them. On passing upwardly through the zinc layer floating on the lead bath, the depth of which is indicated at X in Fig. 10, a uniform adherent coating is formed on the sheets by the alloying action of the zinc with iron of the sheets.

The main reservoir portion of the pot 12, as described in the copending application, Ser. No. 256,684, of Wean et al., permits the accumulation of zinc dross at the bottom thereof at a distance from the exit rolls so that clean metal only will be deposited on the sheets.

If it is desired to increase the depth of the zinc layer through which the sheets pass, in order to increase the thickness of the coating formed on the sheets, this may be done without changing the amount of lead in the tank 10. Zinc is added to the pot 12 in approximately the amount necessary to provide the desired increase in the depth of the zinc layer. The addition of zinc to the pot 12, of course, lowers the lead-zinc interface 79 to some such position as indicated by the dotted line 79'. The pot 12 is then forced downwardly into the pot 10 to about the position shown in Fig. 11. This raises the level of lead in the pot 10 to about the position shown at 50'. The lowering of the pot 12, furthermore, raises the lead-zinc interface to about the position indicated by the dotted line 80 and the surface of the zinc in the pot 12 to about the level indicated by the line 51'.

The housings 53 are then raised by shifting the spacer blocks 54 to positions under the housings instead of above them, as shown in Fig. 11

to bring the axes of the exit rolls 13 substantially to the level of the zinc shown at 51'. The zinc level 51' is then adjusted as closely as possible to the axes of the exit rolls by adding zinc to or bailing it out of the pot 12. This may cause some shifting of the lead-zinc interface 80 and if proper adjustments are made, it will approach the position indicated at 80'. This adjustment provides a zinc layer of a depth Y as indicated in Fig. 11.

It is important that the lead zinc interface be maintained below the upper edge of the reservoir wall 38a because otherwise lead would flow into the reservoir 38. The float stem 75 may be provided with an index of any desired character to indicate the position of the lead-zinc interface by reference, for example, to the eye 76. In other words, if a mark is placed on the stem 75 at the eye 76 when the lead-zinc interface is at the proper position, as illustrated in Fig. 3, the position of the mark on the stem relative to the eye will always show the approximate position of the lead-zinc interface. The float chamber 45 communicates with the housing pocket 44 and both pockets 43 and 44 are open to the lead bath at the ends of the opening in the bottom of the overhanging portion 40 of the pot 12.

A comparison of the depths of the zinc layers indicated at X and Y in Figs. 10 and 11 shows the possible range of adjustment in one particular embodiment. It will be understood, furthermore, that although Figs. 10 and 11 illustrate extreme conditions, proper adjustment of the parts may be made to provide zinc layers of various intermediate depths. The adjustment of the housings 53 and the exit rolls 13 journaled therein requires a corresponding adjustment of the drive therefor but this is readily accomplished by means of the screw shafts 68 and the wedge blocks 66.

It will be observed that to increase the depth of the zinc layer, the pot 12 is lowered. This reduces the elevation of the exit rolls required to produce the desired overall increase in the depth of the zinc layer and thus simplifies the problem of vertical adjustment of the exit roll drive.

The reverse of the procedure described above for increasing the depth of the zinc layer is followed when it is desired to reduce its depth. The described order of operations is not essential, the only necessary precaution being that the lead-zinc interface be not permitted to rise above the upper edge of reservoir wall 38a.

The principal advantage of the invention is that by making the pot 12 adjustable in the pot 10, it is unnecessary to add lead to the pot 10 to balance the increased head of zinc when the depth of the zinc layer is increased. For the change in the depth of the zinc layer from that indicated in Fig. 10 to that shown in Fig. 11, for example, it would be necessary to raise the level of the lead in the pot 10 several inches if the pot 12 were fixed in the pot 10. This would involve the addition of a substantial amount of lead because of the size of the pot 10. A further advantage of the invention is that the zinc is confined within the pot 12. The pot 10, therefore, is not subject to the corroding action of the zinc. The pot 12, being much smaller, can be replaced at relatively small expense when rendered unusable by corrosion of the zinc. At the same time, the heating flame impinging on the walls of the pot 10 does not have direct contact with the pot 12. This reduces the rate of corro-

sion of the pot 12 by the zinc as compared to a zinc pot which is heated by direct impingement of flame thereon. Since the area of the surface of the zinc bath is quite small, the change in the level of the zinc does not involve the handling of much zinc.

The guides 42 are effective in all positions of the rig 12a to receive sheets from guides 23 and direct them accurately into the nip of the exit 10 rolls. Such independently adjustable guides may also be used in a conventional galvanizing machine. It is unnecessary to shift the main rig 11 although it may be removed when desired. The exit rig 12a is adjustable and removable independently of the main rig 11.

Although we have illustrated and described a preferred embodiment and practice of the invention, it will be understood that changes in the construction and procedure disclosed may be made without departing from the spirit of the invention or the scope of the appended claims.

We claim:

1. Apparatus for galvanizing comprising a lead pot, a zinc pot movably disposed in said lead pot and having a bottom opening, posts on said lead pot for guiding vertical movement of the zinc pot therein, and means cooperating with said posts for forcing the zinc pot downwardly.

2. Apparatus for galvanizing comprising a lead pot, a zinc pot movably disposed in said lead pot and having a bottom opening, and means for forcing the zinc pot downward against the buoyance resulting from the displacement of the lead thereby.

3. In a galvanizing apparatus, a pot adapted to contain a heated fluid bath, feed rolls for passing sheet material through said bath, a frame removably disposed on said pot, said rolls being journaled in said frame, a zinc pot removably disposed in said first-mentioned pot, means for securing the zinc pot in vertically adjusted position relative to the first-mentioned pot, exit rolls in said zinc pot, and vertically adjustable means for supporting said exit rolls.

4. In a galvanizing apparatus, a main sheet-feeding rig including bottom rolls adapted to feed sheets therethrough, an exit rig including exit rolls spaced from said bottom rolls, guides on the main rig extending from the bottom rolls toward the exit rolls and other guides on the exit rig extending rearwardly from said exit rolls, said exit rig with said last mentioned guides being adjustable vertically relative to said first-mentioned guides, the discharge ends of the first-mentioned guides extending between the diverging ends of the second-mentioned guides.

5. Apparatus for galvanizing comprising a lead pot, a zinc pot disposed in said lead pot and having a bottom opening, exit rolls in said zinc pot, means mounting said rolls for rotation, means whereby said roll-mounting means may be vertically adjusted relative to said lead pot, driving mechanism for said rolls including a support with a motor thereon, and means for adjusting said support vertically.

6. In a galvanizing apparatus, bottom rolls adapted to feed sheets therethrough, exit rolls spaced from said bottom rolls, guides extending from the bottom rolls toward the exit rolls and other guides extending rearwardly from said exit rolls, the exit rolls and said other guides being mounted on housings adjustable vertically relative to said first-mentioned guides, said other guides flaring rearwardly and being thereby adapted to receive sheets from the first-men-

tioned guides in all adjusted positions of said housings.

7. In a galvanizing apparatus, a main sheet-feeding rig including bottom rolls and guides extending therefrom, an exit rig adjustable vertically relative to the main rig and including exit rolls and guides adapted to direct sheets therebetween, said last-mentioned guides flaring rearwardly to receive the ends of the first-mentioned guides so as to receive sheets therefrom in any adjusted position of the exit rig.

8. In a galvanizing apparatus, a pot adapted to contain a heated fluid bath, feed rolls for passing sheet material through said bath, a main frame removably disposed on said pot, said rolls being journaled in said frame, a second open-bottomed pot disposed in said first-mentioned pot, an auxiliary frame mounted in said second pot, the auxiliary frame being adjustable vertically relative to the main frame, exit rolls journaled in said auxiliary frame, a drive for said exit rolls including a base with a motor thereon, and means for adjusting said base vertically.

9. In a galvanizing apparatus, a pot adapted 25 to contain a heated fluid bath, feed rolls for passing sheet material through said bath, a main

frame removably disposed on said pot, said rolls being journaled in said frame, a zinc pot removably disposed in said first-mentioned pot, an auxiliary frame in said zinc pot, the auxiliary frame being adjustable vertically relative to said zinc pot, exit rolls journaled in said auxiliary frame, a drive for said exit rolls including a base with a motor thereon, and means for adjusting said base vertically and horizontally.

10. 10. In a galvanizing apparatus, a zinc pot, exit rolls journaled in said pot, means whereby said rolls may be adjusted vertically in said pot, a drive for said rolls including a base adjacent the pot with a motor thereon, means for adjusting said base vertically and means for adjusting said base in a horizontal plane, laterally of the pot.

11. In a galvanizing apparatus, a zinc pot, exit rolls journaled in said pot, means whereby said rolls may be adjusted vertically in said pot, a drive for said rolls including a base adjacent the pot with a motor thereon and means for adjusting said base vertically.
